UNITED STATES PATENT OFFICE

128,198

DESIGN FOR A PRINTING PRESS

Adolph Weiss, Brooklyn, N. Y., assignor to Champlain Corporation, Garfield, N. J., a corporation of New York

Application April 24, 1941, Serial No. 100,605

Term of patent 14 years

To all whom it may concern:

Be it known that I, Adolph Weiss, a citizen of the United States, residing at Brooklyn, in the county of Kings and State of New York, have invented a new, original, and ornamental Design for a Printing Press, of which the following is a specification, reference being had to the accompanying drawings which form a part thereof, and in which

Fig. 1 is a front perspective view of a printing press embodying my new design;

Fig. 2 is a rear perspective view of the printing press shown in Fig. 1; and

Fig. 3 is an enlarged perspective view of the upper right hand portion of the machine shown in Fig. 1, with the web removed, the ink reservoir and drying tunnel in open positions, the web guide roller, doctor blade and ink applicator adjusting handles in altered positions and the impression cylinder and its associated supporting parts removed (and placed on the table) so as to show the printing cylinder and ink fountain more clearly.

I claim:

The ornamental design for a printing press, as shown and described.

ADOLPH WEISS.
